We claim the ornamental design for a display screen or portion thereof with transitional graphical user interface, as shown and described.

(51) **LOC (12) Cl.** **14-04**

DESCRIPTION

(52) **U.S. Cl.**

FIG. 1 is a first image of a display screen or portion thereof with transitional graphical user interface showing our new design;

USPC **D14/485**

FIG. 2 is a second image thereof;

(58) **Field of Classification Search**

FIG. 3 is a third image thereof; and,

USPC ..... D14/485—495
CPC G06F 3/048; G06F 3/0481; G06F 3/0482;
G06F 3/04842; G06F 3/04817

FIG. 4 is a fourth image thereof.

See application file for complete search history.

The outer broken lines in the figures depict a display screen or portion thereof and form no part of the claimed design. The remainder of the broken lines in the figures depict portions of the graphical user interface that form no part of the claimed design.

(56) **References Cited**

The appearance of the transitional user interface sequentially transitions between the images shown in FIGS. 1-4. The process or period in which one image transitions to another forms no part of the claimed design.
